UNITED STATES PATENT OFFICE

154,107

DESIGN FOR A CAN OPENER

Joseph B. Donnelly, Burlingame, Calif., assignor
to Schenley Distillers Corporation, New York,
N. Y., a corporation of Delaware

Application December 17, 1947, Serial No. 143,176

Term of patent 14 years

(Cl. D22—2)

To all whom it may concern:

Be it known that I, Joseph B. Donnelly, a citizen of the United States of America, residing at the city of Burlingame, county of San Mateo, and State of California, have invented a new, original, and ornamental Design for a Can Opener, of which the following is a specification, reference being had to the accompanying drawings, forming part thereof.

Figure 1 is a front elevational view of a can opener, showing the new design.

Figure 2 is a side elevational view thereof.

Figure 3 is a top plan view thereof.

Figure 4 is a rear elevational view thereof.

Figure 5 is a reduced perspective view thereof.

I claim:

The ornamental design for a can opener, as shown.

JOSEPH B. DONNELLY.
